(57) **CLAIM**

The ornamental design for a flap cover for bag, as shown and described.

DESCRIPTION

FIG. 1 is a top, front, right side perspective view of a flap cover for bag, showing my new design;

FIG. 2 is a top, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front, left side perspective view of the flap cover for bag shown in a folded configuration;

FIG. 10 is a top, front, right side perspective view of the flap cover for bag shown with an exemplary bag; and,

FIG. 11 is a top, rear, left side perspective view thereof.

The broken lines in FIGS. 10-11 illustrate unclaimed environment and unclaimed portions of the flap cover for bag which form no part of the claimed design, and the broken lines in FIGS. 1-9 illustrate unclaimed portions of the flap cover for bag which form no part of the claimed design.
